(57) **CLAIM**

The ornamental design for a watch buckle, as shown and described.

DESCRIPTION

FIG. 1 is a top perspective view of a watch buckle, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of its combined state thereof;

FIG. 10 is a bottom perspective view of its combined state thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a perspective view showing watch buckle in a position of use with environment; and,

FIG. 18 is an enlarged detail view of area 18 in FIG. 15. The broken lines in the drawings illustrate the portions of the watch buckle, which form no part of the claimed design. The dash-dot-dash broken lines encircling the enlarged views are for annotative purposes only and form no part of the claim thereof.

1 Claim, 18 Drawing Sheets
